UNITED STATES PATENT OFFICE.

WILFRID A. MANCHEE, OF NEWARK, NEW JERSEY, ASSIGNOR TO NEWARK SPRING MATTRESS COMPANY, OF NEWARK, NEW JERSEY, A CORPORATION OF NEW JERSEY.

HAMMOCK-STAND.

1,156,421.

Specification of Letters Patent.

Patented Oct. 12, 1915.

Application filed February 6, 1912. Serial No. 675,862.

To all whom it may concern:

Be it known that I, WILFRID A. MANCHEE, a citizen of the United States, residing at Newark, in the county of Essex, State of New Jersey, have made a certain new and useful Invention in Hammock-Stands, of which the following is a specification.

This invention relates to hammock stands.

The object of the invention is to provide a hammock stand of simple construction, and which is strong, durable, artistic in appearance, and economical to manufacture.

A further object of the invention is to provide a hammock stand of the nature referred to which is capable of being readily knocked down for shipment or storage, and easily erected for use.

Other objects of the invention will appear more fully hereinafter.

20 The invention consists substantially in the construction, combination, location and arrangement of parts, all as will be more fully hereinafter set forth, as shown in the accompanying drawing, and finally pointed 25 out in the appended claims.

In the accompanying drawing,—Figure 1 is a view in front elevation of a hammock support embodying the principles of my invention. Fig. 2 is an end view of the same. 30 Fig. 3 is a broken detail view in section on the line 3—3, Fig. 1, looking in the direction of the arrows.

The hammock stand embodying my invention comprises end frames, each composed of upright members, A and B, separated apart at their lower ends and held and braced in relatively spread or separated relation by a cross connection C. The members A and B are inclined vertically toward 35 each other, the upper end portions, D and E, thereof, being eventually brought into parallel relation with respect to each other, and bolted or otherwise secured together as indicated at F, H. The end frames are connected together at the tops thereof by means 40 of a brace member G, which passes between the pair of ends D, E, of each end frame, the bolt or other securing device F, for securing the upper ends of the portions D, E, 45 together, also passing through the brace or connecting member G as clearly shown. The ends of the member G extend beyond the point of attachment of said member to the upper frame ends D, E, and said extended 50 portions of member G are bent or 55

curved downwardly, as indicated at J, the securing bolts or other securing connections H, for the ends D, E, of the end frames being arranged to pass through the bent end portions J of member G. This construction 60 and arrangement enables me to secure a bracing action, the curved end portions J, of member G, serving as a bracing strut.

If desired, and in order to secure lightness without sacrificing strength or rigidity, 65 the members A, B and G may be made tubular.

It is obvious that the length of the member G determines the extent of separation or distance apart of the end frames of the 70 stand. This distance of separation of the end frames will be dependent, of course, upon the character of the hammock or other support, indicated at K to be suspended or supported by the stand. A convenient arrangement is shown wherein the settee, sofa or other style or form of hammock K, is suspended at its ends from hooks or other securing devices L, from the member G. The distance apart of the hooks L may be 75 80 adjusted or regulated in any suitable or convenient manner as may be desired.

From the foregoing description it will be seen that I provide an exceedingly strong, durable, well balanced and economical structure for a hammock stand. By removing the connecting parts or other securing devices F, H, and the separating members C, the parts comprising the stand may be detached for shipment, storage or transportation in a very small compass, and readily and quickly erected for use.

By extending the ends of the member G beyond the end frames and bending the extended ends downwardly into position to be received and clamped between the upper vertically parallel portions of the end frames A, B, a convenient bracing action is secured as above indicated.

Having now set forth the object and nature of my invention, what I claim as new and useful, and desire to secure by Letters Patent, is:—

1. A hammock stand comprising end frames spaced apart from each other and a member extending between and to which the upper ends of the end frames are secured, said connecting member having integral ends extended beyond the end frames and bent or curved downwardly and rearwardly, 105 110

and secured to said end frames below their upper ends.

2. A hammock stand comprising end frames, each end frame including vertical members inclined toward each other for the lower portion of their length and in parallel relation for the upper portion of their length, said parallel portions of each end frame being detachably secured together and a horizontal connecting member clamped between the upper part of the parallel portions of the end frame members, and having integral ends extended beyond the end frames and bent downwardly and rearwardly into position to be received and clamped between the lower part of the parallel portions of the end frames.

3. A hammock stand comprising end frames each including vertical members separated at their lower ends and brought together at their upper ends, a separating

bar connecting the lower ends of each pair of said vertical members, means for securing together the upper ends of said members, and a horizontal member passing between and connecting the upper ends of one pair of said vertical members to the other upper ends of the pair thereof, said horizontal member having integral extending ends, said extending ends being bent or curved downwardly and rearwardly and received and secured between said frame members at a point below their upper ends.

In testimony whereof I have hereunto set my hand in the presence of the subscribing witnesses, on this 2nd day of February A. D., 1912.

WILFRID A. MANCHEE.
